ASH TRAY

Michael A. Cavalluzzo, Northport, N. Y.

Application May 14, 1948, Serial No. 146,361

Term of patent 7 years

(Cl. D85—2)

To all whom it may concern:

Be it known that I, Michael A. Cavalluzzo, a citizen of the United States, residing at Northport, in the county of Suffolk and State of New York, have invented a new, original, and ornamental Design for an Ash Tray, of which the following is a specification; reference being had to the accompanying drawing, forming a part hereof.

I claim:

The ornamental design for an ash tray, as shown.

MICHAEL A. CAVALLUZZO.
